UNITED STATES PATENT OFFICE.

FREDERICK D. HANSEN AND HERBERT W. TINKER, OF MILWAUKEE, WISCONSIN, ASSIGNEES TO FEDERAL PRESSED STEEL COMPANY, OF MILWAUKEE, WISCONSIN, A CORPORATION OF WISCONSIN.

BRAKE DRUM.

Application filed April 7, 1924. Serial No. 704,767.

To all whom it may concern:

Be it known that we, FREDERICK D. HANSEN and HERBERT W. TINKER, both citizens of the United States, and residing at Milwaukee, county of Milwaukee, and State of Wisconsin, have invented certain new and useful Improvements in Brake Drums, of which the following is a specification.

In the manufacture of brake drums, which are attached to road wheels and other parts of automobiles and the like, discs are cut or punched from a sheet or strip of steel of the required thickness. The discs are placed in a very powerful compression die, which cups the peripheral portion of each disc over to form the annular flange of the drum with which the frictional material of the brake is adapted to contact to effect the proper braking action of the vehicle. When the drums are taken from the die their webs are bowed slightly outwardly, because in the pressing operation the webs are not pressed flat, although the bottom face of the punch may be perfectly flat. We attribute this bowing action to the fact that the edge of the inner die member engages the fillet or corner radius at the juncture of the webs and their flanges and as this fillet or radius is not sharply defined the bottom face of this die member does not press as firmly against the web as it does against the radius. The bottoms also tend to spring outwardly due to some resiliency in the steel. The drums are next placed in another die for the purpose of making the web perfectly flat or giving it a slight concavity, that is pressing the web slightly inwardly past the center of the plane in which the web would lie were it flat. In many cases, it is necessary to subject the drums to the action of the second drum several times in order to give them the proper concavity or flatness, as the case may be, within the small limits required or specified by automobile companies or others. It is recognized by those skilled in the art, that it is difficult, and in many instances impossible, to form the brake drums so that the brake flanges are round or concentric, that is circular within the required limits, and so that the web is symmetrical throughout and free from defective or distortive swells or bulges. The web of the drum, when ap-

plied, seats firmly against the wheel-hub or spokes of the wheel, and it is desirable that this engagement be perfect and that the flange of the drum be truly concentric so that the flange will be truly in alignment with the friction shoe or band of the brake in order that the maximum braking effort is accomplished and equally distributed throughout the flange of the brake drum. It frequently happens in the manufacture of brake drums, as formerly practiced, that the flanges of some drums are so eccentric that is non-circular or "out of round" and the webs have such large bulges or swells causing the eccentricity, that it is necessary to hammer the bulges with a very hammer, to bring the flanges within the acceptable limits of eccentricity. In some instances this cannot be done and then the brake drums are scrapped. We believe that the difficulty in securing drums which have their flanges concentric and their webs symmetrical is due to the fact that during the pressing or forming operation of the discs to cup them to their drum shape unequal strains and stresses are set up in the steel and the excess material in the webs, giving the webs their convex or bowed form, exerts a radial force outwardly tending to distort or throw the flange of the drum out of concentricity. We find that usually these strains are greatest and cause the maximum distortion in the direction in which the steel has been rolled, that is in the direction of the grain of the steel, so that the diameter of the drum is slightly greater in this direction than it is in the transverse direction, thereby tending to give the flange a slight oval or egg-shape form. The distortive swells or bulges in the web also seem to be along this greater diameter. The subsequent die operation, explained above, in some cases tends to bring the flange toward concentricity, that is to say, toward true circular or round form but this cannot always be accomplished and usually not within close limits. The degree of eccentricity that is the extent of deviation from the true circular or round form depends upon certain characteristics of or conditions in the steel, but, as is well known by experts versed in steel making, though not fully understood by them, these character-

- istics or conditions can not be accurately controlled or uniformly regulated or obviated. It has, therefore, been necessary in the past to test or measure the eccentricity of the flange and unevenness of the bearing zone of the web of each and every drum by precision instruments to determine if they are within the prescribed limits and then correct, if possible, the defects in these respects 6
- 10 if the limits are exceeded. The testing and thorough inspection of the drums, the correcting of defects and scrapping of drums which are badly defective materially increase the cost of the drums.
- 15 The principal object of our invention is to provide the webs of steel brake drums with ridges or ribs, preferably radiating ones, in order to more equally distribute the stresses and strains and cause the flanges 20 to be substantially truly concentric and the webs to be substantially perfectly symmetrical. Other advantages of our invention are that the drums are strengthened, and careful tests and inspection are not necessary, thus reducing the cost of manufacture. Still further advantages of our invention 25 will be pointed out hereinafter.
- Referring to the drawings, Fig. 1 illustrates a brake-drum after it has been cupped or formed in and removed from the forming press or compression die; Fig. 2 is an inside elevation of a brake drum embodying our invention; Fig. 3 is a sectional view taken as on the line 3—3 of Fig. 2; and Fig. 4 is 30 a view similar to Fig. 2 but shows a modified form of embodiment of our invention.
- In manufacturing the drum embodying our invention, the disc of steel is pressed or 35 formed in a compression die to the form shown in Fig. 1, in the same manner as drums have been heretofore pressed. In this view we have somewhat exaggerated the convexity of the web of the drum in order to illustrate more clearly the general contour of the pressed drum. The hub or 40 central opening 6 and bolt-holes 7 are then punched in the web and we next put the drum in a suitable die and "bump" it (that is to impart to its web a sharp powerful blow) to give its web the proper concave 45 form and press ribs 8 therein. We preferably form the ribs by depressing the metal inwardly, that is on the inner side of the web, so that they do not interfere with or 50 engage the spokes or wheel hub when the drum is attached to the wheel. The ribs are also preferably tapered so that they are of greater depth at their inner ends than at their outer ends, and hence take up the 55 maximum amount of metal adjacent the hub opening 6 and progressively less outwardly. While we prefer that the ribs shall be straight yet they may be curved, as, for example, illustrated in Fig. 4; or they may 60 be of any other desired and feasible form

or shape. It will be observed in Fig. 4 that the outer bolt holes 10 are radially out of alignment with, or radially between the inner bolt holes 7 and this is made practical by deflecting the outer portions of the ribs. 70

We find that by forming these ribs in the webs of the drum, that the unequal strains and stresses, referred to above, are either equally distributed, neutralized or eliminated. The ribs take up the surplus or excess metal in the web (which excess gave the web of the drum its initial bowed out contour or convexity) and we believe that pulling or inwardly directed forces or strains from the periphery towards the center are set up and they tend to neutralize or counteract the outward strains or forces which seem to be existent in the drum before the ribs are formed in its web. This equalization or elimination of the deforming or distorting strains by the formation of the ribs brings the brake drum flange to its proper true concentricity and at the same time the web is made perfectly symmetrical throughout. We have found by actual demonstration that it is only necessary to "bump" drums by our method once and that the flanges are much more concentric and the webs much more symmetrical than unribbed drums made from exactly the same sheet or strip of steel. It is not necessary to test our drums for concentricity or symmetry or subject them to rigid inspection as the product is uniform and substantially perfect. Thus considerable saving in the cost of manufacture is effected. Furthermore, we have discovered that the ribs, either due to the equal distribution of the strains and stresses or for some other reason, increase the strength of the flanges so that they more readily resist distortion or bending, and this is highly important as they are subjected to considerable force when the braking effort is applied to them, and also to rough handling and use in transportation and by workmen in the factories where the drums are assembled on the automobiles. It will also be obvious that the ribs strengthen the webs of the drums radially and axially and that the ribs increase the width of the bearing surface or edge of the hub opening 6 on the barrel of the wheel-hub, as the ends of the ribs form projections 10 as viewed in Fig. 3. In securing the brake drum to a wheel, the web of the brake drum is drawn up tightly against the flange of the hub by means of bolts extending through the openings 7 between the ribs, and as the segments between the ribs are comparatively narrow adjacent the holes, and separated by the grooves formed by the ribs, the web of the drum is drawn more easily and equally against the wheel and the ribs prevent the web from 100 springing out past its center plane, (after 105 110 115 120 125 130

the fashion of the bottom of a tin dish pan) as is the case in some instances with unribbed brake drums.

While we have shown and described the preferred form of embodiment of our invention as a brake drum with a concave web and radiating ribs pressed inwardly of tapering formation, it is to be understood that our invention is applicable to brake drums having a perfectly flat web throughout or a convex web and that the ribs may not necessarily extend radially or may be pressed outwardly, or may be of uniform depth from one end to the other.

15 We claim:

1. A brake drum formed of steel of uniform thickness, having a brake flange and a web provided with pressed-in ribs adapted to impart substantially true concentricity to 20 said brake flange.

2. A brake drum formed of steel of uniform thickness having a brake flange and a web provided with pressed-in ribs taking up the surplus metal in the web and adapted to 25 impart substantially true concentricity to said brake flange, and substantially perfect symmetry to the web.

3. A brake drum formed of steel of uniform thickness having a brake flange and a

web provided with pressed-in ribs of tapering depth adapted to impart substantially true concentricity to said brake flange.

4. A brake drum formed of steel of uniform thickness having a brake flange and a web provided with ribs extending radially 35 from a central opening in the web and of tapering depth to take up the surplus metal and adapted to impart substantially true concentricity to the flange and substantially perfect symmetry to the web.

5. A brake drum formed of steel of uniform thickness having a brake flange and a slightly concave web provided with pressed-in ribs adapted to impart substantially true concentricity to said brake flange and 45 strengthening the same.

6. A brake drum formed of steel of uniform thickness having a brake flange and a slightly concave web provided with pressed-in radiating ribs taking up the excess metal 50 in the web, the ribs being of tapering depth and adapted to impart substantially true concentricity to said flange and substantially perfect symmetry to said web, and part of the ribs being deflected to accommodate 55 bolt holes in the web.

FREDERICK D. HANSEN.
HERBERT W. TINKER.
